UNITED STATES PATENT OFFICE.

GEORGE HENRY WHEARY, OF RACINE, WISCONSIN.

TRUNK LAUNDRY-BAG AND COVER.

1,378,924.

Specification of Letters Patent. Patented May 24, 1921.

Application filed January 31, 1918. Serial No. 214,564.

To all whom it may concern:

Be it known that I, GEORGE HENRY WHEARY, a citizen of the United States, and resident of Racine, in the county of Racine 5 and State of Wisconsin, have invented new and useful Improvements in Trunk Laundry-Bags and Covers, of which the following is a description, reference being had to the accompanying drawings, which are a 10 part of this specification.

This invention relates to improvements in trunk laundry bag and cover more particularly adapted for use in wardrobe trunks.

In ordinary wardrobe and other trunks 15 no provision is made for covering the garments within the wardrobe section of the trunk to protect them from dust while the trunk is in open position.

Furthermore the ordinary trunk is not 20 provided with means for holding soiled apparel, and if provided with means, said means is not located in a convenient position of accessibility.

It is one of the objects of the present invention to overcome the before mentioned 25 objectionable features and provide a laundry bag and cover which will extend over the garment section of the trunk to protect the garments, said laundry bag and cover 30 being formed with a soiled apparel container into which the soiled apparel may be easily placed or removed therefrom.

A further object of the invention is to 35 provide a trunk laundry bag and cover which may be easily attached to ordinary wardrobe trunks now on the market.

A further object of the invention is to 40 provide a trunk laundry bag and cover which also serves to maintain garments suspended within the wardrobe section of the trunk in position on the hangers.

A further object of the invention is to 45 provide a trunk laundry bag and cover in which the parts may be easily detached from the trunk for cleaning.

A further object of the invention is to 50 provide a trunk laundry bag and cover which is of simple construction, is strong and durable and may be easily mounted within a trunk.

With the above and other objects in view 55 the invention consists of the improved trunk laundry bag and cover and its parts and combinations as set forth in the claims, and all equivalents thereof.

In the accompanying drawing in which

the same reference characters indicate the same parts in all of the views:

Figure 1 is a front view of the wardrobe section of a trunk showing the improved 60 laundry bag and cover mounted therein, parts shown as broken away, the view also indicating by dotted lines a portion of the other section of the trunk;

Fig. 2 is a vertical sectional view thereof 65 taken on the line 2-2 of Fig. 1;

Fig. 3 is a top view of the trunk section shown in Fig. 1, parts of the laundry bag and cover shown broken away;

Fig. 4 is a detail view on a larger scale 70 of the connector bar;

Fig. 5 is a detail view of a modified form of connector; and

Fig. 6 is a detail view of another modified 75 form of connector.

Referring to the drawing the numeral 8 indicates the wardrobe section of a wardrobe 80 trunk, 9 the drawer section and 10 the top cover which is hinged to the drawer section, and forms the top cover for the wardrobe section. The wardrobe section is provided with upper parallel fixed tracks 11, extension tracks 12, garment hangers 13 mounted on the tracks and a swingable shoe box 14 mounted in the lower front portion of the 85 said wardrobe section.

The improved laundry bag and cover 15 comprise a piece of material, such as fabric, which extends horizontally from the upper rear portion of the wardrobe section of the 90 trunk over the garment hangers and the extension rails and then downwardly in front of the wardrobe section and terminating in front of the upper edge portion of the shoe box 14 to which it is easily removably connected by snap buttons 17. The upper rear edge portion of the fabric is in the form of a loop 18 for removably receiving a connecting bar 19 which rests upon the garment hanger tracks 11. The connecting bar is formed of yielding material 100 and is provided on its face with angular hook portions 20 which extend outwardly beneath the tracks and snugly engage the lower surfaces thereof. The connecting bar 105 is also provided with rearwardly and downwardly extending hook members 21 which hook over the upper rear edge of the trunk collar and in connection with the hooks 20 securely hold the bar and the rear edge portion 110 of the fabric in place. The top cover 10 when in closed position as shown in Fig.

2 locks the hook members 21 to the trunk collar.

The vertically extending or front portion of the fabric is of double thickness with the 5 inner portion of considerable fullness to form a laundry bag 22, access to which is through the opening 23. A flap 24 closing said opening is held in closed position by snap buttons 25.

10 By positioning the laundry bag portion in the lower front portion of the wardrobe section, space is utilized which is not ordinarily used and as garments are removed from the hangers and worn the space is gradually automatically increased inwardly for holding 15 the soiled apparel.

The upper or horizontally extending portion of the fabric may also be of double thickness to form a pocket 26 to receive handkerchiefs or other articles of apparel. Said 20 pocket when containing articles also serves as a pad or cushion interposed between the garment hangers and the trunk top cover and into which pad or cushion the garments, 25 draped or folded over the hangers, embed and are yieldingly held in position.

Entrance to the pocket 26 is through the same opening 23 provided for the laundry bag.

30 In the modified form of connector bar 19 shown in Fig. 5 the hook members 21 are omitted and in lieu thereof each hook member 20' is provided with a thumb screw 27 which extends through the outer free end 35 of the hook member and threads into the bar 19 thus providing for clamping the bar 19 directly to the tracks.

In the Fig. 6 modification the hook members are omitted and each end of the bar is provided with a short downwardly extending pin 28 which enters an opening 29 formed in each track.

45 As the fabric extends over the open top and front open side portion of the wardrobe section it forms a protecting cover for the garments suspended from the hangers mounted within said section.

50 From the foregoing description it will be seen that the laundry bag and cover are of very simple construction and are well adapted for the purpose described.

What I claim as my invention is:

1. The combination with a trunk wardrobe section having an open top and front, 55 and a garment hanger track and hangers mounted thereon, of a laundry bag and cover therefor, comprising a material covering the open top and open front portion, said portion covering the open front being in the form of a bag having a front opening, and means 60 connecting the upper and lower edge portions of the material to trunk section portions.

2. The combination with a trunk wardrobe section having an open top and front 65

and a box mounted in the lower portion of the section, the upper portion of said section having parallel tracks mounted therein which are provided with extension tracks foldable to a closed horizontal position and 70 forming the upper forward edge portion of the section, of a laundry bag and cover therefor, comprising a flexible material covering the open top and extending over the extension tracks when in closed position and covering the front opening of the trunk section, said front covering portion being in the form of a bag and having a front opening, means for detachably connecting the lower edge portion of the material to the box, and means 75 for detachably connecting the upper rear edge portion of the material to the trunk section.

3. The combination with a trunk wardrobe section having an open top and front and a 80 box mounted in the lower portion of the section, the upper portion of said section having parallel tracks mounted therein which are provided with extension tracks foldable to a closed horizontal position and 85 forming the upper forward edge portion of the section, of a laundry bag and cover therefor, comprising a flexible material covering the open top and extending over the extension tracks when in folded position and covering the front opening of the trunk section, said front covering portion being in the form of a bag and having a front opening, means for detachably connecting the lower edge portion of the material to the box, and means 90 for detachably connecting the upper edge portion of said material formed with a loop, and a bar removably extending through said loop and having means for detachably engaging the tracks.

4. The combination with a trunk wardrobe section having an open top and front and a box mounted in the lower portion of the section, the upper portion of said section having parallel tracks mounted therein which are provided with horizontally foldable extension tracks foldable to a closed horizontal position and forming the upper forward edge portion of the section, of a laundry bag and cover therefor, comprising a flexible material covering the open top 110 and extending over the extension tracks when in folded position and covering the front opening of the trunk section, said front covering portion being in the form of a bag and having a front opening, means for detachably connecting the lower edge portion of the material to the box, the upper edge portion of said material formed with a loop, and a bar removably extending through said 115 loop and having hook portions for detachably engaging the tracks and the upper edge portion of the trunk section.

5. The combination, with a trunk wardrobe section having an open top which is closed by a hinged cover and also having an 120

- open front which is partly closed by a box mounted in the lower portion of the trunk section, said trunk section having parallel tracks and extensions foldable to a closed 5 horizontal position and forming the upper forward edge portion of the section and garment hangers mounted on the tracks, of a laundry bag and cover therefor comprising a fabric of double thickness covering the open 10 top and extending downwardly from the extension tracks when in folded position and covering the open front portion of the trunk section, said front covering portion forming a bag and having a front opening and said 15 top covering portion forming a container for holding yielding articles which with the covering material form a pad interposed between the hangers and the top trunk cover for maintaining the hangers in position, the 20 lower edge portion of the material having means for detachably connecting it to the box
- and the upper rear edge portion of the material forming a loop, and a bar removably extending through the loop and having means for detachably connecting it to trunk 25 section.
6. The combination with a trunk wardrobe section having an open top and front, and garment hanger tracks and hangers mounted thereon, of a laundry bag and cover 30 therefor, comprising a flexible material covering the open top and front portion of the section, said portion covering the open front being in the form of a bag having an opening, the lower edge portion of the bag part having 35 means for detachable connection with a trunk part, and a bar connected to the upper edge portion of the material and having means for detachable connection with portions of the trunk. 40

In testimony whereof, I affix my signature.
GEORGE HENRY WHEARY.
